UNITED STATES PATENT OFFICE.

EBENEZER K. MACGILLIVRAY, OF CHICAGO, ILLINOIS.

DESIGN FOR A SPOON, &c.

SPECIFICATION forming part of Design No. 20,796, dated June 2, 1891.

Application filed March 23, 1891. Serial No. 386,138. Term of patent 7 years.

To all whom it may concern:

Be it known that I, EBENEZER K. MACGILLIVRAY, a citizen of the United States, and residing at Chicago, in the county of Cook and State of Illinois, have invented and produced a new and original Design for Spoons and other Table Ware, of which the following is a specification, reference being had to the accompanying drawings, forming part thereof, 5 in which—

Figure 1 represents the obverse of a spoon formed after my design, and Fig. 2 a reverse of the same.

My invention relates to an ornamental 15 design for the handles of spoons, knives, forks, &c., especially such as are constructed of metal, and the main feature of the design is in the outer end of the handle which represents an old block-house or fort.

20 In the drawings, A represents the bowl of the spoon, B the handle, and C the outer end or tip thereof. The bowl may be of any ordinary form. The handle or main body B thereof, as shown in the drawings, is shaped 25 to represent the branch of a tree or shrub with the small twigs cut off, thereby leaving slightly-projecting knots, as at b b. The tip C of the handle is made to illustrate an old block-house or fort—such, for instance, as 30 were built for protection in the early history of this country. In the illustration this tip showing the building consists of a lower section c, next to the body of the handle, and an upper section c' of somewhat larger area than 35 the former, so that it projects outward and overhangs the section c. Both of these sections are shaped to represent blocks or logs of wood laid one upon the other to form the struct-

ure. The contour of each section is polygonal. It may be rectangular, if desired. In 40 the lower section c is the representation of a door c², and in the upper section c' loop-holes c³ are represented in the several sides. The larger section c' is surmounted by a roof c⁴, which is slanting and of pyramidal form to 45 correspond to the sides of the building. The surface of the roof is chased to represent shingles. The roof is surmounted by a short cupola c⁵, and at one side of the latter is a short projection c⁶, rising from the roof, representing a flue or chimney. 50

In this design the obverse is intended to show distinctly all the several parts mentioned above, as seen in Fig. 1 of the drawings, and the tip may be made so as to continue the representation of the building around upon the reverse, or the back of the tip may be cut down, so as to leave a substantially smooth surface upon the reverse, as seen in Fig. 2 of the drawings. 60

As already stated, this design is also intended for the handles of knives, forks, and other like table-ware, and the articles may be made of silver or any other metal which is used for this purpose. 65

Having thus described my invention, what I claim as new, and desire to secure by Letters Patent, is—

The design for the body and tip of the handles of spoons, &c., substantially as herein 70 described and shown.

EBENEZER K. MACGILLIVRAY.
